Frank J. Tuttle, ATTORNEY

UNITED STATES PATENT OFFICE.

WILLIAM JOHNSON, OF FREMONT, OHIO.

POST-ANCHOR.

1,089,842.

Specification of Letters Patent. Patented Mar. 10, 1914.

Application filed December 30, 1912. Serial No. 739,413.

To all whom it may concern:

Be it known that I, WILLIAM JOHNSON, a citizen of the United States, residing at Fremont, in the county of Sandusky and 5 State of Ohio, have invented certain new and useful Improvements in Post-Anchors, of which the following is a specification.

The principal purpose and object of my invention is to provide an improved land 10 anchor which is more simple in its construction, and better adapted for use in the anchoring of fence posts, telephone, and other similar posts, than other similar anchors now in use; and I accomplish this purpose by the means which are more particularly hereinafter set forth.

Referring to the drawings which are made a part hereof: Figure 1 represents in perspective a general view of my invention; 20 Fig. 2 represents a longitudinal section of Fig. 1 on the line A--A; the same being shown as in position below the ground line C--C, and the anchor rod suitably turned to enter the slot 2; and Fig. 3 represents 25 a transverse section of Fig. 1 on the line B--B.

Coming now to a more detailed description of my invention: In general terms my invention comprises a cylindrical anchor 30 block 1, which is provided with a slot 2, which from preference extends longitudinally of said block; a reinforcing plate 3, through which said slot 2 is made continuous, and which is provided with recesses 35 4--4, which for manifest reasons are located opposite each other, one on each side of the slot 2, and made to connect therewith; and an anchor rod 5. Manifestly, the plate 3 might be made integral with the block 1, the part 1 being made suitably 40 heavy; but from preference, considering the strength and weight, I mount said plate upon the inner side of said block, and secure the same thereto by means of bolts or rivets 45 6. For the purpose of engaging said recesses 4--4, I provide said rod with side lugs, 7--7. Said anchor block being cylindrical, in the practical use of my invention, I bore a hole in the ground to receive said 50 anchor. In order that my invention shall have its greatest value, it is intended that said rod shall be inserted through the native earth; and therefore, said lugs being necessarily placed near one of its ends, that end 55 is suitably sharpened, and in consequence

given a harpoon appearance. Said hole being first bored, it may now be understood from Fig. 2, that in order that said point shall be permitted to enter the slot 2, said rod must be suitably turned. In construction, it may now be stated, that said slot 2, and the harpoon point 8, are co-adapted so that said point can enter said slot only when the rod is suitably turned; and so that when the same is given a quarter turn 60 either way, said lugs may then be made to enter said recesses. In practical construction it may be understood, that, said hole being first bored, it is immaterial whether the "anchor" is then placed therein, or the 65 rod is next inserted. But from practical experience I find it most convenient to leave the anchor until the rod has first been inserted; thereby obviating any necessity for the use of special appliances for holding said anchor while the rod is being inserted. But in either event, after said "point" has been made to enter said slot, and said rod is given a quarter turn, by slightly withdrawing 70 said rod and causing said lugs to enter said recesses, said rod is effectually locked, and all tampering therewith is prevented. For the purpose of making connection with the 75 guy wire, not shown, the outer end of said rod is provided with a suitable eye 9.

In referring to the drawings it may be noticed that in Fig. 2, which is a vertical section of Fig. 1, that the anchor is set angling. It may now be explained that in 80 said drawing, said anchor is supposed to be in position for actual use, which according to the character of the soil requires that said hole shall be bored, and consequently that said anchor shall be set, with a more or less close approximation to that of a 85 right angle to said guy wire.

Having now fully described my invention, what I claim as new, is:

In a land anchor an anchor block, a reinforcing plate fixedly carried thereby, a slot passing through said block and plate, and duplicate locking recesses in said plate, one at each side of said slot and connecting therewith.

In testimony whereof I affix my signature in presence of two witnesses.

WILLIAM JOHNSON.
